UNITED STATES PATENT OFFICE.

JOHN A. MACQUARRIE, OF SAN FRANCISCO, CALIFORNIA, ASSIGNOR TO ELEONORA
MINETTI, OF SAN FRANCISCO, CALIFORNIA.

DESIGN FOR A STATUE.

Application filed March 17, 1924. Serial No. 8,972. Term of patent 7 years.

To all whom it may concern:

Be it known that I, JOHN A. MACQUARRIE, a citizen of the United States, residing in the city and county of San Francisco and State of California, have invented a new, original, and ornamental Design for a Statue, of which the following is a specification, reference being had to accompanying drawing, forming part thereof.

Fig. 1 is a front elevation and Fig. 2 is a side elevation of a statue showing my new design.

I claim:

The ornamental design for a statue as shown.

JOHN A. MACQUARRIE.
